PAUL G. DORN, OF COLDEN, NEW YORK

SKID CHAIN

Application filed December 2, 1929. Serial No. 411,120.

This invention relates to improvements in skid chains for automobiles and more particularly to an improved cross chain made up of a plurality of interfitting and interlocking 5 readily detachable links.

One of the objects of the present invention is to provide a skid cross chain of the above general character which will be strong and durable in construction, and which may be 10 inexpensively manufactured and assembled.

A further object is to provide a chain of the above character in which the links may be readily replaced, removed or added as circumstances might require or according to the 15 size of the tire to which the complete chain is applied.

A further object is to provide a chain of the above character in which the links may be disengaged or disconnected only when the 20 complete chain is removed from the tire, thereby positively preventing loss of links when the tire is in use.

A further object is to provide a cross chain which will act like a mud hook or skate by 25 reason of its peculiar construction and relatively large lateral engaging area.

A further object is to provide a cross chain of the above character having a relatively large flat surface adapted to engage the tire, 30 thereby to prevent excessive wear on the tire, as well as specially shaped side areas adapted to prevent lateral movement of the wheel without excessive wear on the road surface.

Other objects will be in part obvious from 35 the annexed drawing and in part hereinafter indicated in connection therewith by the following analysis of this invention.

This invention accordingly consists in the 40 features of construction, combination of parts, and in the unique relation of the members and in the relative proportioning and disposition thereof, all as more completely outlined herein.

To enable others skilled in the art to fully 45 comprehend the underlying features thereof that they may embody the same by the numerous modifications in structure and relation contemplated by this invention, a drawing 50 depicting a preferred form of the invention 55 has been annexed as part of this disclosure,

and in such drawing, like characters of reference denote corresponding parts throughout all of the views, of which—

Fig. 1 is a perspective view showing a portion of the entire skid chain with two spaced 55 apart series of links or cross chains embodying the present invention;

Fig. 2 is a plan view of the road engaging surface of one link;

Fig. 3 is a reverse view showing the manner 60 of separating two adjacent links;

Fig. 4 is a view showing the position of two adjacent links in position for disengagement.

Referring now to the drawing in detail, 5 indicates the circumferential portions of a 65 complete skid chain, which portions may be of any desired character; and these form no part of the present invention except in so far as they may enter into the general combination, that is, it is immaterial whether it is a 70 wire link structure or a continuous wire or the like providing it constitutes a means to which the ends of the cross links may be connected.

Each cross chain is composed of a plurality 75 of links, all of which are exactly alike with one exception, as hereinafter noted. As shown in Fig. 3, each link comprises a substantially U-shaped channel member, of which the under face of the bottom wall or 80 cross portion provides a relatively large flat tire engaging surface 6. The side walls or flanges 7 of the channel member, Fig. 2, are preferably inclined at their ends from the upper face of the bottom wall, as indicated 85 at 8. The inner faces of the side wall 7 are inclined upwardly in the direction of the outer faces of the walls, as denoted by the lines 10. The resulting braced construction

provides a stronger and more durable arrangement as well as providing two surfaces adapted to more efficiently engage the pavement or ice along which the wheel is rolling, thus acting as a skate or mud hook. The surfaces 8 prevent lateral slip of the wheel without causing excessive wear on the road surface.

Each link is provided with coacting fastening means such as a hole or slot 11 and at 95 its opposite end with a curved hook 12 as 100

shown in Fig. 4. The rear surfaces 6 of each link is notched at one or both sides of the slot 11 as indicated at 13, Fig. 3, whereby the extreme end of the hook 12 will have a close sliding lateral fit at it is moved transversely with respect to the adjacent link. In separating the links, they are preferably moved to the acute angle position shown in Fig. 4 whereby the two inclined surfaces 8 abut each other. This prevents accidental separation of the links when in use and precludes unintended removal of the chain from the wheel.

In order to provide a securing means at each end of the cross chain for engaging the peripheral members 5, it is desirable that one of these links 14 be provided with a hook at each end as shown at the extreme left of the cross chains in Fig. 1. This link 14 of course may be placed anywhere in the cross chain as desired, in which case the adjacent links of the type shown in Fig. 2 would have to be reversed when assembled.

It will be noted particularly that a link of this character having inclined end surfaces 8 is more desirable than an ordinary link with turned-up square side edges in that the widened and sloping parts 8 provide a more effective surface against lateral movement as well as one which will not unduly wear the road surface. The links are preferably made of iron or drop forge steel and may be very inexpensively manufactured and assembled, and when so assembled provide a strong and durable skid chain which will, by reason of the length of the slots and hooks 11 and 12, maintain its alignment and will not kink or separate as long as the peripheral chains remain in position. In other words, there is an interlocking engagement between the parts whereby they can not be disconnected until the skid chain is removed from the tire. The invention is therefore well adapted to accomplish, among others, all of the objects and advantages herein set forth.

Without further analysis the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

I claim:

1. A non-skid cross chain of the character set forth comprising a plurality of links, each including a substantially U-shaped channel having a continued bottom wall and side walls extending therefrom, the under face of the bottom wall engaging the tire, the inner faces of said side walls being inclined towards the outer faces thereof, the ends of each side wall being inclined towards opposite ends and from the upper face of the bottom wall, and complementary means on adjacent links for connecting the same, the inclination of the ends of the side walls being such that adjacent links may be turned to a facing relation and moved laterally for connection or disconnection.

2. A non-skid cross chain of the character set forth including a plurality of links, each comprising a substantially U-shaped channel having a bottom wall and side walls extending therefrom, the under face of the bottom wall engaging the tire, the inner faces of said side walls being inclined towards the outer faces thereof, the side walls being inclined at their ends from the upper face of the bottom wall, the bottom wall having a transverse slot near one end and a tongue extending from the other end for insertion through the slot of an adjacent link, the inclination of the ends of the side walls being such that adjacent links may be turned to a facing relation and moved laterally for connection or disconnection.

3. A non-skid cross chain of the character set forth including a plurality of links, each including a substantially U-shaped channel having a continued bottom wall extending therefrom, the under face of the bottom wall engaging the tire, the inner faces of said side walls being inclined towards the outer faces thereof, the ends of each side wall being inclined towards opposite ends and from the upper face of the bottom wall, the bottom wall having a transverse slot near one end and a transverse groove on the under face thereof opening into said slot, a tongue extending from the other end of the bottom wall for insertion through the slot of an adjacent link, the end inclination of the side walls being such that adjacent links may be turned to a facing relation and moved laterally for connection and disconnection, the end of the tongue being accommodated in said groove during such lateral movement.

Signed at Colden, New York, this 27th day of November, 1929.

PAUL G. DORN.
